COMBINED DRESS AND SCARF

Bernard Hurwitz, New York, N. Y.

Application September 16, 1950, Serial No. 12,222

Term of patent 3½ years

(Cl. D3—26)

To all whom it may concern:

Be it known that I, Bernard Hurwitz, a citizen of the United States of America, residing in New York, county of New York, and State of New York, have invented a new, original, and ornamental Design for a Combined Dress and Scarf, of which the following is a specification, reference being had to the accompanying drawing, forming part thereof,

Fig. 1 is a front view of a combined dress and scarf showing my new design.

Fig. 2 is a rear view thereof.

Fig. 3 is an enlarged view of one of the panels shown in Figure 1.

I claim:

The ornamental design for a combined dress and scarf, substantially as shown.

BERNARD HURWITZ.
